[57] **CLAIM**

The ornamental design for a football helmet hitch plug, as shown and described.

DESCRIPTION

FIG. 1 is a perspective view of a football helmet hitch plug showing my new design;

FIG. 2 is a front elevational view of the football helmet hitch plug;

FIG. 3 is a side elevational view of the football helmet hitch plug;

FIG. 4 is a rear elevational view of the football helmet hitch plug;

FIG. 5 is an opposite side elevational view of the football helmet hitch plug;

FIG. 6 is a top plan view of the football helmet hitch plug;

FIG. 7 is a bottom plan view of the football helmet hitch plug; and,

FIG. 8 is a perspective view, shown at a reduced scale, of the football helmet hitch plug mounted on the hitch of a vehicle. The broken line showing of a vehicle is for illustrative purposes only and forms no part of the claimed design.
